[57] CLAIM

The ornamental design for a photoviewer, as shown and described.

DESCRIPTION

FIG. 1 is a perspective view, as viewed from the front top of a photoviewer showing our new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof;
FIG. 8 is a front elevational view thereof illustrating the photoviewer in open position;
FIG. 9 is right side elevational view thereof with the cover in the open position, the pages in spread position and the support extended; and,
FIG. 10 is a perspective view thereof as viewed from the bottom left, with the cover in open position.
